UNITED STATES PATENT OFFICE.

JOHN J. DEWEY, OF HARTFORD, VERMONT.

FEED-WATER REGULATOR.

1,045,821.

Specification of Letters Patent.

Patented Dec. 3, 1912.

Application filed December 23, 1909. Serial No. 534,570.

To all whom it may concern:

Be it known that I, JOHN J. DEWEY, a citizen of the United States, residing at Hartford, county of Windsor, and State of Vermont, have invented an Improvement in Feed-Water Regulators, of which the following description, in connection with the accompanying drawing, is a specification, like characters on the drawing representing like parts.

This invention relates to a device for regulating the feed water to a boiler and particularly to a device adapted for this use in steam automobiles.

One familiar way of feeding water to the boiler of a steam-driven automobile is by the use of a pump which is driven from the engine or from the driving gear and which acts to force the water from the water tank into the boiler. Where this arrangement is used it is customary to provide a by-pass from the delivery pipe of the pump back to the tank and to provide a valve in said by-pass for opening and closing it. This by-pass is used because the pump is operating continuously whether it is necessary to deliver water to the boiler or not. When the by-pass valve is open the pump merely operates to force water around through the by-pass into the tank again; but when the by-pass valve is closed, the only outlet from the pump leads into the boiler and the pump will force water into the boiler. In some previous devices of this character it has been proposed to provide for opening and closing the by-pass valve automatically by the action of an expansion tube which is connected to the boiler so that it will be filled with steam or water according to the water level in the boiler, and which when filled with steam will expand and thereby cause the by-pass valve to close, while when filled with water will contract thereby permitting the valve to open.

My invention relates to a device of this latter class and has for its objects to provide an exceedingly simple device which has few moving parts and is not liable to get out of order; and also to provide a novel construction whereby when the water level is at its normal point, the pump will be set in operation to pump water into the boiler whenever the automobile is going down a grade, and its operation will be stopped when the automobile is ascending a grade. This is of decided advantage because the

power necessary to pump water into the boiler is a considerable factor and where the boiler feed mechanism is so arranged that the power necessary to force the water into the boiler can be used when the automobile is going down grade, a considerable saving in the cost of operating can be effected.

Referring now to the drawings wherein I have shown one embodiment of my invention, Figure 1 is a side view of an automobile body partially broken out to show a boiler feed mechanism embodying my invention; Fig. 2 is a side view of the expansion tube for operating the by-pass valve; Fig. 3 is a section on the line *x-x*, Fig. 2; Fig. 4 is a section on the line *y-y*, Fig. 2; Fig. 5 is a diagrammatic view showing the position of the expansion tube.

3 indicates an automobile body which may be of any suitable or usual construction, 4 indicates a boiler, 5 the water tank and 6 the pump which operates to pump the water into the boiler. The pump is shown diagrammatically only as its construction and operation is well known, and it was thought advisable not to confuse the drawings by showing the pump in detail.

The pump is connected to the tank 5 by means of a pipe 7 and is also connected to the boiler 4 by a pipe 8 which will preferably have a check-valve 9 therein, said pipe being shown as leading into the top of the boiler, although it might equally well lead into any part of the boiler. Leading from the pipe 8 is a by-pass 10 which extends back to the tank 5 and this by-pass has a by-pass valve therein, the valve casing of which is shown at 11. The by-pass valve may be of any suitable shape, and I have herein shown it as a needle valve 12 which seats onto a valve seat formed in the valve casing 11. When the by-pass valve is closed, the pump must necessarily pump water into the boiler through the pipe 8, but when the by-pass valve is open, the pressure in the boiler will close the check-valve 9 and the pump will then operate to pump the water around through said by-pass and by-pass valve 12 back to the tank 5.

In order to provide for opening and closing the by-pass valve automatically, I employ an expansion tube 13 which is rigidly connected at one end to the valve-stem 12 and is connected at the other end to the valve casing 11. This may conveniently be

accomplished by securing the two ends of the expansion tube 13 to two headers 14 and 17, one of which is secured to the stem of the valve 12, and the other of which is secured to two rods 16 that in turn are secured to the valve casing 11. The header 17 is shown as provided with the two wings 18 through which the rods 16 extend and to which said rods are rigidly secured by set-nuts 19. The header 14 is provided with wings 15 through which the rods 16 extend so that said header may slide on the rods. Said rods extend through ears 20 formed on the valve casing 11 and are yieldingly secured to said ears by check-nuts 21 and springs 22, said springs being confined between the ears and the nuts 23 on the ends of the rods. The header 17 is connected to the top of the boiler by a pipe 24 and the header 14 is connected to the bottom of the boiler by a pipe 25.

The expansion tube 13 is arranged horizontally, as seen in Fig. 5, and will be situated at approximately the normal water level of the boiler, which is indicated in the drawings by the dotted line 27. With this construction it will be noted that the expansion tube 13 is in constant communication both with the top and the bottom of the boiler, and as a result the water level in the pipes 24, 25 and expansion tube 13 will be the same as that in the boiler. When the water level in the boiler is above the normal water line 27, the expansion tube will be filled with water, but when said water level is below the line 27, the expansion tube will be filled with steam. The temperature of the steam in the boiler is, of course, higher than that of the water in the pipe 25, and the parts of the apparatus are so adjusted that when the expansion tube 13 is filled with water and consequently has the temperature of the water, the valve 12 will be opened. As soon as the water level falls below the expansion tube, however, and said expansion tube becomes filled with steam, the higher temperature of the steam will cause said tube to expand and the increase in length of this expansion tube, due to the expansion, will cause the head 14 to slide on the rod 16 and move the valve 12 until the latter is closed. If the tube has any further expansion after the valve is closed, such expansion is taken care of by the springs 22. As soon as the by-pass valve is thus closed the pump 6 will obviously operate to pump water into the boiler, and when the water level in the boiler rises to such a point that the expansion tube will be filled with water instead of steam, said tube will cool somewhat and will consequently contract in length. The contraction will open the by-pass valve 12, thus permitting the water to be pumped around through the 65 by-pass instead of into the boiler.

It will thus be seen that the apparatus as herein described will operate to open and close automatically the by-pass valve upon variations in the water level in the boiler, and the operator of the machine, therefore, does not have to burden his mind with the question of water supply in the boiler.

While the expansion tube and by-pass valve may be placed in any convenient location on the automobile, I prefer to place it in the rear of the boiler and at a slight distance therefrom, as illustrated in the drawings, wherein it is placed immediately behind the dash-board 30. The advantage of placing it in the rear of the boiler is that the operation of pumping into the boiler will be started up automatically when the automobile is going down hill and will be stopped when the automobile is going up hill, unless, of course, the water level is much below its normal position when the automobile is going up the hill. The reason for this is that when the automobile is going down hill the expansion tube will be brought into a position above the normal water level due to the inclined position of the automobile body, so that the water level will fall in the pipe 25 and steam will enter the expansion tube, thus opening the by-pass valve. As soon as the automobile begins to ascend a grade, the expansion tube, being in the rear of the boiler, is at a lower level than the normal water level in the boiler and becomes filled with water, thus opening the by-pass again.

The power necessary to pump water into the boiler against the high pressure therein is a considerable factor and if the pumping can be done when the automobile is going down grade and requires comparatively little power to propel it instead of while it is going up grade, a considerable saving in the water and gasolene used can be effected. Indeed if the down grade is sufficient no power is needed to propel the car, and as the pump is usually connected to the driving gear so as to operate whenever the car is going, the pumping may be done without operating the engine and simply by the coasting movement of the car down the grade. Of course, if the automobile is going up a long grade it will be necessary to pump water into the boiler some time during the ascent, but the average road over which an automobile passes is full of short grades and with this arrangement the pumping of the water into the boiler will under normal conditions be done almost entirely while the automobile is going on the down grades. Moreover whenever water is pumped into the boiler, the temperature of the water in the boiler is reduced and considerable heat energy is required to bring the water to the previous temperature. With my improvements wherein the pumping is done on the 130

down grade, this heating of the water which is pumped into the boiler is done at a time when little or no power is needed to run the automobile, and it is therefore possible to 5 maintain at all times a comparatively even steam pressure.

In the drawings I have shown the pipes 24 and 25 situated partially in the rear of the dash-board 30 simply to avoid confusion 10 but in actual practice these pipes would be concealed in the boiler space in front of the automobile.

Since the expansion tube is connected directly to the valve stem without the interpolation of levers, springs, etc., the device is an 15 extremely simple one and there are no parts that are liable to get out of order.

Having fully described my invention, what I claim as new and desire to secure by 20 Letters Patent is:—

In an automobile, the combination with a boiler, a pump to pump water into the boiler, a by-pass from the pump to the

source of supply and a valve in the by-pass having a stem and provided with a valve 25 casing, of guide rods yieldingly connected at one end to said valve casing, a horizontally-arranged expansion tube situated at approximately the normal water level in the boiler having one end thereof rigidly connected to the other end of said rods, the other end of said tube being rigidly connected directly to the valve stem, and means connecting one end of the tube to the top of the boiler and the other end of the tube to the 35 bottom of the boiler whereby said tube will fill immediately when the water level falls below normal.

In testimony whereof, I have signed my name to this specification, in the presence 40 of two subscribing witnesses.

JOHN J. DEWEY.
